Primary Examiner — Michelle E. Wilson*Assistant Examiner* — Messina L Smith(74) *Attorney, Agent, or Firm* — Carmody Torrance
Sandak & Hennessey LLP(57) **CLAIM**

The ornamental design for a casket, as shown and described.

DESCRIPTION

FIG. 1 is a side perspective view of a casket showing my new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom thereof.

The broken lines shown in the drawings depict portions of the casket that form no part of the claimed design. The broken lines shown in FIG. 7 define a region therein that forms no part of the claimed design.

1 Claim, 3 Drawing Sheets(56)
